Claims priority, application Switzerland Apr. 15, 1957

10 Claims. (Cl. 68—205)

The present invention relates to yarn guiding and treating apparatus.

It is known to treat yarn by winding the same on a pair of rotary substantially parallel shafts which advance the yarn convolutions axially along the shafts, one of these shafts having a treating liquid applied to its outer surface to contact the yarn so as to treat the same. Such apparatus may be used for many purposes such as complete coagulation, de-acidifying, de-sulfurizing, washing, bleaching, and finishing the yarn. While it is very desirable to be able to carry out a pair of successive yarn treatments on the same shaft by applying different treating liquids to discrete successive surface portions of a shaft which are successively engaged by the yarn, up to the present time the problem has not been satisfactorily solved because of the difficulty in maintaining the liquids at the pair of surface portions of the shaft separate from each other. While the problem of simply preventing the liquid on one portion of such a shaft from having access to the liquid on the next portion of the shaft is in itself simple to solve by placing a suitable barrier between the successive shaft portions, the difficulty arises in guaranteeing that the yarn moves properly past such a barrier. In other words, this barrier must on the one hand be capable of maintaining the liquids separate from each other and on the other hand be capable of permitting the yarn to be advanced efficiently from one of the surface portions to the next surface portion. For example, a soft, easily compressible barrier of rubber or the like located between successive surface portions of a shaft which carry different treating liquids cannot successfully operate to prevent the yarn from being retarded in its movement along the shafts while at the same time maintaining the treating liquid separate from each other. Such an elastic, easily deformable barrier of soft rubber or the like has been shown in practice to be incapable of functioning properly. Furthermore, manual transfer of the yarn from one of the treating surface portions to the next surface treating portion of a shaft also is completely impractical and has proved to be of no use in actual practice.

One of the objects of the present invention is to provide a fully automatic apparatus which for the first time makes it possible for successive surface portions of a shaft to carry different treating liquids which are reliably maintained separate from each other and which also makes it possible for the yarn to pass without any hindrance and automatically from one to another of the surface portions which respectively carry different treating liquids.

Another object of the present invention is to provide an apparatus of the above type which will automatically form a bundle of yarn at the end of one of the treating surface portions of a rotary shaft, which will then rapidly advance this bundle to the next treating surface portion of the shaft, while maintaining different treating liquids respectively located at the surface portions separate from

2

each other, and which will reliably prevent movement of the yarn in a reverse direction.

A further object of the present invention is to provide an apparatus of the above type which is of a simple rugged construction, which is composed of a relatively small number of parts, and which is very reliable in operation.

With the above objects in view the present invention includes in an apparatus for guiding and treating yarn,

10 a pair of substantially parallel rotary shafts which are spaced from each other and about which a loop extends to which one end of a yarn which is helically wound on the shafts is connected, this loop and the yarn convolutions connected thereto advancing along the rotary shafts, 15 as is well known in the art. One of these rotary shafts has a pair of successive surface portions which are adapted to have applied thereto a pair of different treating liquids for treating the yarn, and this shaft carries between its successive surface portions, in accordance 20 with the present invention, a sling ring means which maintains the two treating liquids separate from each other. The sling ring means of the present invention is formed with a gap which is inclined oppositely to the inclination of the helical convolutions of the yarn, and this gap of the sling ring means receives the loop and the yarn and advances the same past the sling ring means from one surface portion of the shaft to the next surface portion 25 of the shaft. The present invention also includes a yieldable means located between the shafts and aligned with the sling ring means, and this yieldable means is first engaged by the loop to yieldably prevent the same from moving to the gap of the sling ring means so that yarn convolutions which follow the loop become located next to the loop to form a bundle therewith, then the yieldable 30 means yields automatically to free the bundle for axial movement along the surface so that the bundle is received in the gap of the sling ring means and is rapidly advanced thereby to the next surface portion of the shaft which carries the sling ring means, whereupon the yieldable 35 means returns to its rest position where it prevents the yarn which has moved past the sling ring means from returning to the gap thereof.

The novel features which are considered as characteristic for the invention are set forth in particular in the 45 appended claims. The invention itself, however, both as to its construction and its method of operation, together with additional objects and advantages thereof, will be best understood from the following description of specific embodiments when read in connection with the 50 accompanying drawings, in which:

Fig. 1 is a fragmentary elevational view of part of an apparatus of the present invention;

Fig. 2 is a sectional view taken along the line II—II of Fig. 1 in the direction of the arrows;

Fig. 3 shows the position which part of the structure of Fig. 2 takes immediately after it has the position shown in Fig. 2;

Fig. 4 is a fragmentary sectional plan view of an embodiment of a yieldable means of the present invention which is different from that of Figs. 1—3;

Fig. 5 is a partly sectional elevational view of an embodiment of a sling ring means different from that of Figs. 1—4; and

Fig. 6 is a fragmentary elevational view of a third embodiment of a sling ring means according to the present invention.

Referring now to Figs. 1 and 2, there are illustrated a pair of substantially parallel elongated rotary shafts 1 and 2 of equal diameter which are rotated in a known way in the same direction respectively about their axes and at the same speeds. Although these shafts 1 and 2

are substantially parallel, actually their axes, when projected onto a common plane normal to the plane of Fig. 1, cross over each other and are inclined at a very slight angle with respect to each other in a known way. A yarn 3 which is to be continuously treated in succession with different treating liquids has a starting end formed into a closed loop 4, or the starting end of the yarn 3 may be connected with a special closed loop 4 made of rubber string, or the like. The closed loop 4 extends between and passes partly around the shafts 1 and 2, and the convolutions of the yarn 3 also extend between and pass partly around the shafts 1 and 2, as is evident from Figs. 1 and 2. In a known way, this arrangement causes the loop 4 and the yarn convolutions 3 connected thereto to advance from right to left, as viewed in Figs. 1 and 2.

The shaft 2 is provided with discrete successive surface portions 5, 6, 7 separated from each other by a plurality of sling ring means 8, in accordance with the present invention. These surface portions 5, 6, 7 of the shaft 2 respectively have different treating liquids applied thereto, and these treating liquids are continuously supplied to the surface portions of the shaft 2, respectively, in a known way.

Each of the sling ring means 8 of the present invention is in the form of a spiral rib fixed to the shaft 2 and extending through slightly more than one convolution about the shaft 2. It will be noted that the rib 8 is of substantially V-shaped cross section and has its crest located distant from the axis of the shaft 2, so that any treating liquid which reaches the rib 8 will be centrifugally thrown away from the shaft 2, and in this way the treating liquids on the successive surface portions of the shaft 2 are maintained separate from each other by the several sling ring means 8. This construction of the sling ring means provides between the free overlapping end portions of each sling ring means a gap 9 which extends along a helix which is inclined oppositely to the inclination of the convolutions of the yarn 3. For example, the gap 9 of each sling ring means extends along a right hand helix while the convolutions of the yarn 3 extend along a left hand helix. It is this gap 9 of each sling ring means which permits the loop 4 and the yarn convolutions to move automatically from one treating surface portion of the shaft 2 to the next treating surface portion while the sling ring means still operates to maintain the different treating liquids separate from each other.

A yieldable means of the present invention is located between the shafts 1 and 2 in alignment with each of the sling ring means 8, and this yieldable means functions first to temporarily prevent the loop 4 from advancing to the gap 9 so that successive convolutions of the yarn 3 become located next to the loop 4 and form a bundle therewith, for then yielding to free this bundle for movement into the gap 9 so that the sling ring means 8 then operates similar to a feeding screw to rapidly advance the entire bundle to the left, as viewed in Fig. 1, beyond the sling ring means, and finally the yieldable means prevents the advanced bundle from returning to the gap 9.

In the embodiment of Figs. 1 and 2 this yieldable means includes a carrier in the form of a stationary bar 10 located between the shafts 1 and 2 and being substantially parallel to the axes thereof. In this embodiment the yieldable means further includes an elongated rubber tubular member 11 which is elastically bendable and which is located in a plane normal to a straight line extending across and substantially perpendicular to the axes of the shafts 1 and 2. This is, in other words, the plane of Fig. 2. The bar 10 fixedly carries a pin 10a which extends into one end of the elastic tube 11 so as to support the latter on the bar 10, and the other end of the elastic tube 11 receives a pin 12d fixed to a substantially U-shaped member 12 for supporting the latter on the elastically bendable elongate member 11. The sub-

stantially U-shaped member 12 of the yieldable means is also located in the plane which is normal to a straight line extending across and being substantially perpendicular to the axes of the shafts 1 and 2, and in this plane the member 12 has an intermediate elongated substantially straight portion 12a, a right elongated free end 12b, and a left elongated free end 12c. These elongated free ends 12b and 12c are oppositely inclined with respect to each other and are inclined away from each other. They extend from the intermediate portion 12a toward the plane which includes the axis of shaft 2 and the straight line perpendicular to this axis and the axis of the shaft 1.

The yieldability of the tubular member 11 is carefully chosen so that this structure operates in the following manner:

As may be seen from the left portion of Figs. 1 and 2, the loop 4 which advances from right to left first engages the elongated free end 12b of the yieldable means and is temporarily prevented by the yieldable means from advancing to the gap 9 of the sling ring means. During this time several of the convolutions of the yarn 3 which succeed the loop 4 become located next to the same to form a bundle therewith, and simultaneously the tube 11 bends to an increasing extent toward the left, as viewed in Figs. 1 and 2, as a result of the force acting on the loop 4 and the yarn 3 to advance the latter toward the left. Thus, the loop 4 and some of the yarn convolutions which have become located next to the loop 4 approach closer and closer to the gap 9 of the rotating sling ring means 8 and finally the bundle enters into the gap 9, the yieldable means momentarily taking at this time the position illustrated in Fig. 3. At this moment the sling ring means 8 acts similar to a feeding screw and advances the bundle to the left, as viewed in Figs. 1-3, so that the bundle advances over the junction between the portions 12a and 12b of the member 12. The bundle is thus advanced to the left at a greater speed, and at the same time the tube 11 straightens due to its inherent resiliency and the member 12 returns to its rest position. The yieldable means at the right portions of Figs. 1 and 2 is shown in its rest position where the portion 12a of the member 12 extends substantially parallel to the axis of the shaft 2. It will be noted that with the member 12 in its rest position the left leg 12c thereof prevents the yarn convolutions from returning to the gap 9 of the sling ring means 8. In this way, the structure of the invention solves the problem of automatically advancing the yarn from one treating surface portion of the shaft to the next treating surface portion while at the same time guaranteeing that the different treating liquids at the successive treating portions are maintained separate from each other.

In the above-described example of the present invention the yarn guide member 12 of the yieldable means has a relatively small circular cross section and thus has a very low inertia. It is conceivable to construct the member 12 in the form of a rotatable body, for example.

It is not essential that the bendable elastic member 11 take the form of a rubber tube. It can, for example, take the form of a coiled steel wire spring. It is sufficient if it is laterally bendable to the desired extent. It is of course necessary that the member 11 as well as all other parts of the structure resist reaction with the treating liquids which may take the form of acids as well as alkalis and bleaching mediums. Some of the parts of the structure may, for example, be made out of glass.

Fig. 4 shows a different embodiment of a yieldable means according to the present invention. The member 13 of this embodiment corresponds to the member 12 and is of a substantially V-shaped cross section in the plane of Fig. 4 which is normal to a straight line extending between and substantially perpendicular to the axes of the shafts 1 and 2. This member 13 has an exterior surface 13a which engages the yarn in a manner similar to the portion 12a of the member 12. A pin 14

is fixed to and extends from the member 13 toward the bar 10, and this pin 14 is axially shiftable in a sleeve 15 having an end flange fixed to the bar 10 by suitable screws or the like, as shown in Fig. 4. A spring 16 is coiled about the sleeve 15, engages the flange of sleeve 15, and also engages the member 13 to urge the latter away from the bar 10 to the rest position shown in Fig. 4. The sleeve 15 fixedly carries a transverse crosspin 18 which extends through an elongated axial slot 17 of the pin 14 so as to guide the latter and member 13 for axial movement while preventing turning of members 13 and 14. Of course, the pin 18 may be fixed to the pin 14 and extend through a slot of the sleeve 15, and an end of the slot 17 will determine the rest position of member 13. The oppositely inclined surfaces of member 13 which are engaged by the loop 4 and the yarn 3 meet at a rounded apex of the member 13. This member 13 operates similarly to the member 12. Thus, the loop 4 and the yarn 3 which is advanced toward the left, as viewed in Fig. 4, first engages the right inclined surface of member 13 which gradually moves toward the bar 10 simultaneously compressing the spring 16 to an increasing extent, and a bundle of yarn is formed next to the loop 4 at this time, and this yarn bundle together with the loop 4 passes over the rounded crest of member 13 while simultaneously being received in the gap 9 of the sling ring means 8 to be advanced to the left beyond the member 13 which is then returned by the spring 16 to its rest position, and in this position the left surface 13b prevents the yarn from returning to the gap 9 of the sling ring means.

Fig. 5 illustrates another embodiment of a sling ring means of the present invention. This embodiment is constructed similarly to a screw type pump impeller and is made up of a plurality of blades 19 each of which extends along part of a helix which extends about the axis of the shaft 2, and these blades 19 are distributed circumferentially about the shaft 2, as shown in Fig. 5. Each pair of successive blades 19 defines a gap 20 through which the bundle composed of the loop 4 and some of the convolutions of the yarn 3 passes in the above-described manner. This sling ring means of Fig. 5 is made up of two or more segments having hub portions 22 located next to each other in a circumferential groove 23 of the shaft 2, and aligned grooves of the hub portions 22 receive a pair of snap rings 21 which retain the several parts of the sling ring means in assembled condition in the groove 23.

The sling ring means may also take the form of a simple circular ring carried by the shaft 2 and having a cylindrical outer surface interrupted by one or more helically inclined grooves each of which forms a gap which functions in the same way as the gap 9.

Fig. 6 discloses still another embodiment of a sling ring means. This sling ring means takes the form of a helically wound ring 24 which extends through slightly more than one revolution and which has its overlapping free end portions located directly next to each other so that they do not form a gap as is the case with the embodiment of Figs. 1-4. The ring 24 is made from an elongated channel member of substantially U-shaped cross section which has a pair of side walls interconnected by a base wall which is located next to and fixed with the shaft 2. The side walls of the channel 24 extend away from the axis of the shaft 2 and define between themselves the gap 25 which receives the bundle to advance the same axially from one treating surface to the next treating surface of the shaft 2. The leading end of the channel 24 which first receives the bundle, shown at the right end of channel 24 in Fig. 6, is of inclined wedge-shaped configuration so that the yarn passes freely into the gap 25 without engaging any corners of the channel member 24.

It will be noted that the above-described structure of the invention not only operates automatically and efficiently, but in addition it is quite inexpensive.

It will be understood that each of the elements described above, or two or more together, may also find a useful application in other types of textile treating apparatus differing from the types described above.

5 While the invention has been illustrated and described as embodied in a yarn guiding and treating apparatus, it is not intended to be limited to the details shown, since various modifications and structural changes may be made without departing in any way from the spirit 10 of the present invention.

Without further analysis, the foregoing will so fully reveal the gist of the present invention that others can by applying current knowledge readily adapt it for various applications without omitting features that, from the 15 standpoint of prior art, fairly constitute essential characteristics of the generic or specific aspects of this invention and, therefore, such adaptations should and are intended to be comprehended within the meaning and range of equivalence of the following claims.

20 What is claimed as new and desired to be secured by Letters Patent is:

1. In an apparatus for guiding yarn and treating the same with different treating liquids, in combination, a pair of rotary shafts spaced from and substantially parallel to each other for advancing an endless loop extending between and passing partly around both of said shafts and a yarn connected at one end to said loop and wound partly around both shafts and extending therebetween so that the rotary shafts advance the loop and the yarn 25 connected thereto along said shafts while contacting the same, one of said shafts having a pair of consecutive outer surface portions adapted to have different treating liquids applied thereto for treating the yarn as it advances along said surface portions; and sling ring means carried 30 by said one shaft between said surface portions thereof for maintaining different treating liquids respectively located at said surface portions separate from each other, said sling ring means being formed with a gap inclined oppositely to the inclination of the convolutions of the 35 yarn for receiving the yarn and guiding the same past said sling ring means to prevent said sling ring means from retarding the movement of the yarn axially along said shafts, the ends of said sling ring means adjacent said gap overlapping each other in circumferential direction.

45 2. In an apparatus for guiding yarn and treating the same with different treating liquids, in combination, a pair of rotary shafts spaced from and substantially parallel to each other for advancing an endless loop extending 50 between and passing partly around both of said shafts and a yarn connected at one end to said loop and wound partly around both shafts and extending therebetween so that the rotary shafts advance the loop and the yarn connected thereto along said shafts while contacting the same, one of said shafts having a pair of consecutive outer surface portions adapted to have different treating liquids applied thereto for treating the yarn as it advances along said surface portions; sling ring means carried 55 by said one shaft between said surface portions thereof for maintaining different treating liquids respectively located at said surface portions separate from each other, said sling ring means being formed with a gap inclined oppositely to the inclination of the convolutions of the 60 yarn for receiving the yarn and guiding the same past said sling ring means to prevent said sling ring means from retarding the movement of the yarn axially along said shafts and said sling ring means being located opposite a continuous surface portion of the other of said shafts; and yieldable means located between said shafts 65 in alignment with and spaced from said sling ring means and having a rest position yieldably preventing the movement of the loop to said gap of said sling ring means until a plurality of convolutions of the yarn become located next to the loop to form a bundle therewith, for 70 then automatically moving yieldably away from said 75

rest position so that the bundle advances into said gap of said sling ring means and is rapidly advanced thereby beyond said yieldable means, and for then returning automatically to said rest position where said yieldable means prevents the yarn from returning to said gap of said sling ring means.

3. In an apparatus as recited in claim 1, said sling ring means being in the form of a helical rib fixed to said one shaft, having a length equal to slightly more than one convolution.

4. In an apparatus as recited in claim 1, said sling ring means being in the form of a helically curved channel of substantially U-shaped cross section, having a pair of side walls interconnected by a base wall, said base wall engaging said one shaft and said side walls extending from said base wall away from the axis of said shaft and defining said gap between themselves.

5. In an apparatus as recited in claim 1, said sling ring means being in the form of a plurality of blades distributed circumferentially about said one shaft, each being inclined substantially along a helix with respect to said one shaft, and each pair of successive blades defining between themselves said gap of said sling ring means.

6. In an apparatus as recited in claim 2, said yieldable means including a substantially U-shaped member located substantially in a plane normal to a straight line extending across and substantially perpendicular to the axes of said shafts, said U-shaped member having an intermediate substantially straight elongated portion and a pair of elongated end portions inclined oppositely with respect to each other and extending from the ends of said central portion toward a plane which includes the axis of one of said shafts and said straight line, one of said elongated end portions engaging said loop and the plurality of successive convolutions of the yarn to form said bundle and the other of said elongated end portions preventing the yarn from returning to said gap.

7. In an apparatus as recited in claim 6, said yieldable means further including a stationary carrier located between said shafts and an elongated elastically bendable member connected at one end to said stationary carrier

and at its opposite end to said intermediate portion of said substantially U-shaped member, said bendable member also being located substantially in said plane normal to said straight line.

8. In an apparatus as recited in claim 7, said carrier being in the form of an elongated stationary bar which is substantially parallel to the axes of said shafts.

9. In an apparatus as recited in claim 7, said bendable member being in the form of an elongated rubber tube, said carrier fixedly carrying a pin which extends into one end of said tube and supports the latter and said substantially U-shaped member fixedly carrying at its intermediate portion a second pin which extends into an opposite end of said rubber tube for connecting said substantial U-shaped member therewith.

10. In an apparatus as recited in claim 2, said yieldable means including a member which is of substantially V-shaped configuration in a plane normal to a straight line extending across and substantially perpendicular to the axes of said shafts, said V-shaped member having a rounded apex and a pair of legs extending from said apex toward a plane which includes the axis of one of said shafts and said straight line, and spring means for yieldably urging said member away from the latter plane to a rest position, the bundle formed by the loop and the successive plurality of yarn convolutions located next to the same engaging one of the legs of the V-shaped member until the spring yields upon movement of said member toward said plane including said straight line and shaft axis so that the bundle passes over the rounded apex when the bundle is received in said gap, the other leg of the V-shaped member preventing the return of the yarn to said gap.
